UNITED STATES PATENT OFFICE.

WILLIAM F. PERSONS, OF CLEVELAND, OHIO, ASSIGNOR TO THE GUIDE MOTOR LAMP MANUFACTURING COMPANY, OF CLEVELAND, OHIO, A CORPORATION OF OHIO.

SIDE LAMP FOR AUTOMOBILES.

Application filed May 31, 1923. Serial No. 642,445.

To all whom it may concern:

Be it known that I, WILLIAM F. PERSONS, a citizen of the United States, residing at Cleveland, in the county of Cuyahoga and State of Ohio, have invented a certain new and useful Improvement in Side Lamps for Automobiles, of which the following is a full, clear, and exact description, reference being had to the accompanying drawings.

This invention relates generally to automobile lamps and more particularly to lamps known as side lamps and usually arranged upon the cowl of the automobile.

The object of the invention is to provide a simple and highly efficient means for securing the glass and retaining ring or door to the casing, and another object is to so construct such means that they may be quickly and easily released whenever it is desired to replace the glass or the electric bulb.

Another object is to so construct such fastening means that they will not detract from the attractiveness or ornamentation of the design of the lamp as a whole.

With these various objects in view, the invention consists in the details of construction of the various parts and in the manner of combining or arranging the same all of which will be fully described hereinafter and set forth in the appended claims.

In the drawings forming a part of this specification, Fig. 1 is a vertical sectional view of a side light embodying one form of my invention; Fig. 2 is a horizontal view of the same, and Fig. 3 is a section on the line 3—3 of Fig. 2.

In carrying out my invention I employ a lamp casing A which is substantially cylindrical in shape and is formed with a slightly flaring and shouldered front edge B. In connection with the lamp casing, I employ a channeled sheet metal frame or ring C which fits over the flared and shouldered front edge of the lamp casing A as most clearly shown in Figs. 1 and 2. The inner and front edge C' of the ring or frame is intended to contact with the lens or glass D while the rear and outer edge C² rests adjacent to or contacts with the flared and shouldered edge of the lamp casing. The rear edge C² extends rearwardly and inwardly as shown and engag-

ing said rearwardly and inwardly extending portion C² are the outwardly turned hook portions E² of a yoke or stirrup E which extends rearwardly and has an apertured central portion E' arranged adjacent the rear wall of the lamp casing and the aperture in this member E' is threaded as most clearly shown in Fig. 1, there being an enlargement or thickening at this point for the purpose of providing a sufficient number of threads.

The glass D contacts with the inner forward edges C' of the ring or frame C as previously described and within the legs of the yoke or stirrup and in order to hold the glass from the inner side, I employ a ring F fitting over the yoke or stirrup, within the channeled ring C and also within the flared and shouldered front of the casing, said ring being provided with radially inwardly projecting fingers F' which are upset in order to engage the outer edge of the glass D, as most clearly shown in Figs. 1 and 3, and it will be noted that two of these fingers are arranged at diametrically opposite points and that the others are arranged in spaced pairs at opposite points, the space between the pairs receiving the leg of the stirrup or yoke therebetween, and in this manner the ring is properly positioned with reference to the yoke or frame and is held against rotation.

When the frame, stirrup, glass and ring have been thus assembled, they are inserted in the lamp casing and then a screw G passing through the rear of the casing screwed into the rear portion of the yoke or stirrup and draws the frame C firmly against the glass and also the ring F firmly against the flared and shouldered front of the casing and in consequence binds the glass D securely between the two and all of the parts are thus securely connected together.

When it is desired to replace the electric bulb or to replace the glass D, it is only necessary to remove the screw G and lift the frame together with the glass ring and stirrup or yoke from the casing.

In assembling the parts, the yoke or stirrup which has a certain amount of inherent elasticity, is first sprung into engagement with the channeled frame C. The glass is then positioned upon the frame and

the ring F is then arranged upon the glass and stirrup within the frame C and all of these parts inserted into the casing and the screw projected through the rear end 5 of the casing and secured into the threaded portion E' of the yoke or stirrup fastening all of the parts securely together.

Having thus described my invention, what I claim is:—

- 10 1. The combination with a lamp casing, of a channeled frame having inwardly extending front and rear edges, a glass contacting with the front edges of said frame, a yoke having hooked forward ends contacting with the rear edges of said frame, a ring arranged upon said yoke and within the frame and having inwardly projecting fingers contacting with the glass and means arranged at the rear end of the casing 15 for drawing the yoke toward the rear end thereof and locking the frame upon the front end thereof.
- 15 2. The combination with a lamp casing, of a channeled frame having inwardly extending front and rear edges, of a flared and shouldered front edge, 25 a glass contacting with the front edges of said frame, a yoke having hooked forward ends adapted to be sprung into engagement with the rear edges of the frame, a ring carried upon the hooked ends of the yoke and within the channeled frame, said ring having a plurality of upset inwardly projecting fingers 30 adapted to engage the edges of the glass and a screw passing through the rear of the casing and engaging the rear end of the yoke for drawing said yoke toward the rear end and locking the frame upon the front end of the casing.

In testimony whereof, I hereunto affix my signature.

WILLIAM F. PERSONS.
